CLAIM

The ornamental design for a heart necklace, as shown and described.

DESCRIPTION

FIG. 1 is a front, right, and top perspective view of a heart necklace, showing our design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a part of a heart ornament.

FIG. 10 is a partial enlarged view of an area labeled 10 in FIG. 3 comprising the heart ornament; and,

FIG. 11 is a partial enlarged view of an area labeled 11 in FIG. 2 comprising the heart ornament.

The dash-dot broken lines forming circles in FIGS. 1, 2, 3, 9, 10 and 11 represent partial enlarged views. The dash-dot broken lines between the chain segments represent a break line, which depicts a symbolic break in the length of the heart necklace.

The dash-dash broken lines on the back of the heart ornament in FIG. 2 and FIG. 4 illustrate portions of the pendant. The broken lines, and the appearance of any portion of the article between the break lines, form no part of the claimed design.
